Primary Examiner — Messina L Smith

CLAIM

The ornamental design for a milk frother, as shown and described.

DESCRIPTION

FIG. 1 is a front, top perspective view of a milk frother, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the milk frother, showing in an alternative positions; and,

FIG. 10 is an enlarged view of a portion of the milk frother showing detail 10 identified in FIG. 1.

The dashed lines in the figures illustrate portions of the milk frother that form no part of the claimed design. The dash dot dash lines in. FIGS. 1 and 10 are for the purpose of illustrating the enlarged view indicators and form no part of the claimed design.

1 Claim, 10 Drawing Sheets
